(57) **CLAIM**

The ornamental design for a medical monitoring device, as shown and described.

DESCRIPTION

FIG. 1 is a perspective view of the top, front and right side of a medical monitoring device showing my new design;

FIG. 2 is a front view thereof;

FIG. 3 is a rear view thereof;

FIG. 4 is a left side view thereof;

FIG. 5 is a right side view thereof.

FIG. 6 is a top plan view thereof; and,

FIG. 7 is a bottom plan view thereof.

The broken lines are used to illustrate portions of the medical monitoring device that form no part of the claimed design.
